UNITED STATES PATENT OFFICE

JOHN G. WHITNEY, OF ELYRIA, OHIO

DISPLAY DEVICE

Application filed March 22, 1930. Serial No. 437,965.

This invention relates to merchandise display devices.

One of the objects of this invention is to provide a display device which will be attractive in appearance, simple and cheap to construct and efficient in operation.

Another object is to provide a merchandise display device upon which a great number of articles of merchandise such for example as neckties and other similar articles may be displayed and each article rendered visible without the necessity of handling of the same by the customer.

Another object is to provide such a merchandise display device upon which the articles of merchandise which it is adapted to display may be quickly and easily placed or removed therefrom and which when thereon will be retained thereon in an orderly arrangement.

Another object is to provide a merchandise display device of the class referred to upon which a large number of articles such as neckties for example may be displayed in a small space and which will clearly indicate when one or more of the articles have been removed therefrom, to discourage theft of the articles by shoplifters which occurs when articles of merchandise are displayed collectively.

Another object is to provide a merchandise display device provided with improved means for illuminating the articles thereon and provided with improved means for letter press display of quality, price, etc.

Other objects will be apparent to those skilled in the art to which my invention pertains.

My invention is fully disclosed in the following description taken in connection with the accompanying drawing in which,

Fig. 1 is a side elevational view of a display device embodying my invention in one form thereof with some of the parts broken away;

Fig. 2 is a partial cross-sectional view taken from the plane 2 of Fig. 1 and drawn to a large scale;

Fig. 3 is a partial cross-sectional view taken from the plane 3 of Fig. 1 or Fig. 5 and drawn to a larger scale;

Fig. 4 is a view taken from the plane 4-4 of Fig. 1;

Fig. 5 is a fragmentary view similar in general to Fig. 1 but showing a modification of my invention.

Referring to the drawing I have shown at 1 a tubular post or pedestal provided with a supporting base 2. Telescoped upon the support 1 and axially slideable thereon is a head 3. With the parts in position shown, the support 1 extends part way only into the head 3 and therefore the head 3 may be adjusted upwardly or downwardly on the support 1. A collar 4 provided with a thumb screw 5 may be adjustably positioned upwardly or downwardly on the support 1 and secured in any adjusted position. The lower end of the head 3 rests upon the collar 4 and is supported thereby. The upper side of the collar 4 has a lug 6 and the lower end of the head 3 is cut away to provide a pair of shoulders 7-7. By this construction, the head 3 may be, at any adjusted position, rotated upon the support 1 and about its axis and its rotational movement in either direction may be limited by abutment of the stops 7 upon the lug 6. Preferably I provide a rotational movement of approximately 180 degrees.

Upon the upper end of the head 3 is secured as by threads 8, a thimble 9 to which are connected a pair of flexible electric conduits 10-10 carrying on their outer ends electrical lamp bulbs and reflectors indicated generally at 11-11. Insulated wires for supplying current to the lamps may pass downwardly through the conduits 10, through the sleeve or head 3, tubular post 1, base 2 and outwardly therefrom to a connection plug 12.

By limiting the rotational movement of the head 3 and the lamps connected therewith and rotated therewith, to an angle of 180 degrees, the possibility of twisting the lamp cords and breaking or entangling them is avoided.

Clamped upon the head 3 intermediate its ends is a double bracket 13 comprising a pair of outwardly projecting downwardly sloping arms 14-14 and an intermediate attachment portion 15. The arms 14-14 and portion 15 are preferably formed from flat bar stock

and are in a plane but the portion 15 is formed at a point midway between the arms 14—14 with a transverse depression 19 substantially fitting the exterior cylindrical surface of the head 3. A clamp 16 also partly encircles the head 3 and is riveted to the portion 15 by rivets 17—17. Thus the arms 14—14 are provided with a cylindrical bore through which the head 3 is telescoped and the arms 14 may 10 thus be adjustably moved or slid upwardly and downwardly on the head 3. To secure them in any such elevated position, a thumb setscrew 18 is threaded through the portion 15 and engages the head 3. The rotational position of the arms 14 around the axis of the support 1 may also be adjusted and fixed by the same means.

The arms 14—14 are provided with a plurality of spaced perforations 21, two of which 20 are indicated in Fig. 1 through which are inserted a corresponding plurality of transverse rods 22. The rods may be press-fitted into the perforations 21 or otherwise rigidly secured therein so that they are disposed in 25 parallel relation to each other. Any suitable number of rods, such as five for example, may be provided on each of the arms 14, the rods of one arm 14 being parallel to each other and parallel to the rods on the other arm 14. The 30 rods 22 are all preferably of the same length and extend equal distances from the arms 14 on each side thereof. At the ends of each of the rods 22 a large diameter disk or head 23 is provided. The head 23 may be secured 35 to the rods in any suitable manner but I prefer to provide heads 23 with a shank or pin and drive the same into the rods 22. In this connection the rods 22 may be tubular.

Mounted upon the arms 14—14 is a pair 40 of card supporting clips 24—24, of the well-known construction shown in Fig. 1, adapted to frictionally clamp display cards 25 therein upon which may be printed display matter relating to price, quality, etc. of the goods 45 to be displayed. The clips 24 may be secured upon the arms 14—14 by means of screws in the screw-threaded holes 26—26 shown in Fig. 3.

The operation of my invention as shown 50 in Figs. 1 to 4 inclusive may be well described in connection with articles of merchandise such as neckties. The neckties are mounted on the rods 22 as indicated in dotted lines 55 in Figs. 1 and 4. To mount a necktie on the rod the necktie may be suspended on the thumb and first finger of the user's hand and slipped or passed over the head 23 on the end of the rod and placed upon the rod. The head 23 will thereafter prevent the necktie 60 from sliding off the end of the rod. It is desirable in the practice of my invention that each article such as a necktie shall occupy a place on the rod 22 by itself, that is, they will not be placed one on top of the other. To permit of this and at the same time to

make possible the display of a great number of articles in a compact space, the plurality of rods 22 of suitable length is provided. On a display device of the general proportions illustrated in the drawing, there may be provided room for a dozen ties on each rod 22 and thus ten dozen ties may be displayed on the complete device. 70

By thus providing a device upon which a great number of ties may be displayed, each tie being displayed separately, I obtain several important advantages and improvements over prior display devices. Each tie or like article may be seen and examined by the prospective purchaser without the necessity of his handling any of the ties, that is, none of them is concealed by others. The ties may be arranged over the whole display device as to color and gradations of color whereby a desired color or shade may be 80 quickly and accurately found. By providing a place for each tie, it is practically impossible for the commission of a theft by the so-called shop lifter because the salesman can instantly detect the fact that a single tie 85 is removed because its blank space will immediately be apparent on its rod 22. Any selected tie may be removed from the device without disturbing the display or disarranging the other ties and there are no 90 obstructions to the removal of any tie of the entire lot. The rods 22 being separated throughout the length, particularly at the ends thereof, the ties may be mounted on the rods without the necessity of threading their ends through the rods. The sloping arrangement of the groups of rods 22, permits the equal illumination of the ties by the lamps 11 and at the same time concealing the 95 lamps from the observer. The arms 14—14 being rotatable around the standard 1, gives 100 access to ties on both sides of the device. 105

In the modification of my invention shown in Fig. 5, many of the features of the first described form are retained but with simplification. The lamps 11—11 are not employed and the head 30 is rotatable continuously in one direction, there being no stops on the lower end of the head 30 nor on the collar 31, but the head 30 may be adjusted upwardly 115 or downwardly. The upper end of the head in this form is provided with a single clip 32 and a single display card 33.

My invention is not limited to the exact 120 details of construction as shown and described. Many changes may be made therein without departing from the spirit of my invention or sacrificing its advantages.

I claim:

1. In a merchandise display device, a 125 standard, a head telescopically mounted on the standard vertically adjustable thereon and rotatable about the axis thereof, means telescopically mounted on said head, a laterally extending arm supported thereby, 130

a plurality of bars secured to the arm and extending horizontally therefrom in parallel spaced relation to each other.

2. In a merchandise display device, a standard, a head telescopically mounted on the standard vertically adjustable thereon and rotatable about the axis thereof, means telescopically mounted on said head, a laterally extending arm supported thereby, a plurality of bars secured to the arm at their middle portions and extending horizontally therefrom in opposite directions and in parallel spaced relation to each other.

3. In a merchandise display device, a standard, a head telescopically mounted on the standard vertically adjustable thereon and rotatable about the axis thereof, means telescopically mounted on said head, a plurality of sloping arms extending laterally therefrom on opposite sides thereof, a plurality of bars secured to each arm at substantially the middle portions of the bars and extending horizontally from the arms in opposite directions and in spaced parallel relation to each other.

25 4. In a merchandise display device, a standard, a head telescopically mounted on the standard vertically adjustable thereon and rotatable about the axis thereof, means telescopically mounted on said head, a plurality of sloping arms extending laterally therefrom on opposite sides thereof, a plurality of bars secured to each arm at substantially the middle portions of the bars and extending horizontally from the arms in opposite directions and in spaced parallel relation to each other, the bars being provided each with heads on the extreme ends thereof.

40 5. In a merchandise display device, a standard, a head telescopically mounted on the standard vertically adjustable thereon and rotatable about the axis thereof, means telescopically mounted on said head, and a laterally extending arm supported thereby, a plurality of bars supported by the arm and extending horizontally in parallel spaced relation to each other.

In testimony whereof I hereunto affix my signature this 19th day of March, 1930.

50 JOHN G. WHITNEY.
